UNITED STATES PATENT OFFICE.

JOE P. PANOS, OF VERONA, WISCONSIN.

SHOOTING-GALLERY.

1,250,215.

Specification of Letters Patent. Patented Dec. 18, 1917.

Application filed July 17, 1916. Serial No. 109,835.

To all whom it may concern:

Be it known that I, JOE P. PANOS, a citizen of the United States, residing at Verona, in the county of Dane and State of Wisconsin, have invented certain new and useful Improvements in Shooting-Galleries, of which the following is a specification.

This invention relates to targets, and more particularly to an improved device of this nature, wherein the target comprises a plurality of figures which are movably mounted and therefore when the figures are shot at, the skill of the marksman is tested to a greater degree.

The invention has more especial reference to a construction of the character stated, wherein a plurality of figures are caused to traverse a predetermined course and are successively displayed before the marksman to be shot at.

More particularly, the present invention has reference to the novel construction and arrangement of the moving figures which constitute the targets, and the means for moving the same; the targets comprising a plurality of figures representing mounted riders, so positioned upon their mounts that when struck by a projectile they will be moved from their seats or saddles, thus giving the impression of falling; the means for moving the mounts, including flexible members, which are alternately moved forward, such movement causing the legs of the horses to be manipulated, consequently giving the appearance of walking or trotting horses.

Still further, the invention embraces a novel form of target which is arranged upon the body of the rider, the same being connected with mechanism carried by the body of the rider, which will release a catch and permit the said rider to fall to one side when hit.

Another important characteristic of the invention resides in the provision of means for automatically remounting the riders, subsequently to their dislodgment, this means comprising an elevated inclined trackway which is arranged adjacent the track and adapted to receive and support the portion of the body of the rider thereon; thus as the horse is advanced the rider will be gradually moved to an upright position upon the mount and the catch engaged, whereupon the device is again ready for display.

Among the aims and objects of the inven-

tion, may be recited the provision of a target of the character mentioned, with a view to compactness and in which the number of parts are few, the construction simple, and the cost of production small.

Other objects and advantages will appear from the following specification, reference being had to the accompanying drawings in which:

Figure 1 is a fragmental top plan of my improved target showing one of the various riders dislodged from his mount and resting upon the automatic remounting means,

Fig. 2 is a fragmental elevation partly in section showing the rider displayed to be shot at and a portion of the means whereby the mounts are moved,

Fig. 3 is a vertical section taken on the line 3—3 of Fig. 2,

Fig. 4 is a detail transverse section showing the driving means whereby the mounts are moved about their supporting platform, and Fig. 5 is a detail in elevation showing the manner in which the hoofs of the various mounts are connected with the propelling chain, whereby they may be successively advanced.

Referring now more particularly to the drawings in which like reference numerals refer to corresponding parts throughout the several views, I provide a supporting base comprising a platform having top and bottom portions 1 and 2 respectively, and suitable side walls whereby the top and bottom are spaced apart. A screening or division wall 3 is supported upon the top portion 1 of the platform adjacent the front thereof, and has formed in the same, an opening 4. This opening provides means whereby the various figures or targets may be successively displayed to be shot at. Upon the top portion 1 I arrange a plurality of circularly disposed rollers 5 which are journaled for rotation upon the vertically arranged studs 6 which are secured to said top portion 1. About the circularly disposed rollers 5 and concentric therewith, I arrange a second set of similarly disposed rollers, which are designated 7, these rollers being mounted for rotation upon studs 8 which are in turn affixed to the top portion 1.

By this arrangement, it is evident that I have provided a plurality of circular trackways, or more specifically, a circular inner track-way and a similar outer trackway, the purpose of this arrangement being pres-

ently described. With a view toward providing for means whereby the targets may be moved the construction of which targets will be subsequently entered into, I arrange 5 about the outer and inner circular trackways as constituted by the rollers 5 and 6, a plurality of flexible linked chains 9 and 10 which are preferably of the sprocket type. Spaced apart parallel rings 11, 11' and 12 and 12' are arranged above the sprocket 10 chains 9 and 10 and are secured to the top portion 1 of the platform in any suitable manner, thus providing for means whereby vertical movement of said chains 9 and 10 15 will be prevented. It will be noted that the chains are at all times maintained in proper circular position by means of their respective rollers 6 and 7, the rollers also constituting sufficient bearing means therefor.

20 With reference to the propelling means whereby the circular sprocket chains 9 and 10 may be moved, I employ means whereby motion will be alternately imparted thereto, the said means comprising a plurality of 25 gears 13 and 14 which are fixedly mounted upon vertically disposed shafts 15 and 16, these shafts being journaled within the top and bottom portions 1 and 2 of the platform. Upon the upper extremities of the shafts 30 15 and 16, which as will be noted, extend above the top portion 1 a slight distance, I mount sprocket wheels 17 and 18, the teeth of which are engaged with the various links of the sprocket chains 9 and 10. Gear wheels 35 19 and 20 are constantly enmeshed with the gears 13 and 14 and are fixedly mounted upon vertically disposed shafts 21 and 22, which, as will be obvious, are journaled within the top and bottom portions 1 and 40 2. The lower extremities of the shafts 21 and 22 project below the bottom portion 2 and carry thereupon a plurality of gears which I shall designate by the numerals 23 and 24, which gears are normally enmeshed 45 with similar gears 25 and 26, these gears being mounted upon stub shafts 27 and 28, which are secured to the underface of the bottom portion 2 by means of bolts as generally indicated by the numeral 29. The gear 50 25 has arranged adjacent thereto and mounted upon the lower portion of its shaft 28, which as will be obvious extends below the same, a sprocket wheel 30, about which is arranged a driving sprocket chain 31. The 55 chain 31 may be extended forwardly into engagement with any suitable prime mover, not shown, whereby the necessary power may be transmitted to the structure in order that the same may be operated. In order that 60 the gear 26 may be driven, an idle gear 32 mounted upon a stub shaft 33, which is affixed to the lower face of the bottom portion 2, is enmeshed therewith and with the gear 25. Thus, as the said gear 25 is rotated, 65 the motion in turn will be transmitted

therefrom through the idler 32 through the gear 26 and then onto the gear wheel 24. As above stated the circular chains 9 and 10 are moved alternately so as to cause the legs 34 to be successively manipulated, and to this end attention is directed to the fact that the teeth on the gear wheels 19 and 20 are spaced farther apart than are the teeth on the gears 13 and 14. By this arrangement, as the gear wheels 19 and 20 are rotated, the succeeding teeth thereon will impart a step by step movement to the respective gears 13 and 14 and hence cause the same to be successively rotated and consequently impart the desired movement to the chains 9 and 10. 70 75 80

The targets, the construction of which will be now entered into, comprise figures, representing horses, which are indicated generally by the numeral 34. The fore and rear 85 legs of the horses 34 are pivoted to the body portion as at 35, thus allowing the same to swing backwardly and forwardly. Certain of the links of the chains 9 and 10 have affixed to the top portions thereof, upright pins 36 to which the hoofs of the horses are pivotally secured as at 37. As the chains 9 and 10 are moved, the legs of the horse will be successively moved forwardly, thus giving the impression that the animal is walking or trotting. The rider in the form of a manikin, is seated upon the horse and is generally indicated by the numeral 38 as will be evident, the legs of the rider straddle the body of the horse in the usual manner. However, the leg 39 is pivotally secured to the body portion of the figure as at 40 and is yieldably held in position adjacent the body of the horse by means of a contractile spring 41, one end of which is attached 90 to said leg while the remaining portion is secured to the body of the horse. The body of the rider is concaved as at 42 in order that the same may snugly fit the body of the horse and is pivotally secured thereto by 95 means of a pin 43. To provide for means whereby the body of the rider may be normally maintained in upright position upon the horse, I arrange upon the body of the latter a keeper 44 which is adapted to be 100 engaged by a pivotally mounted catch member 45 carried upon the body of the rider within the vertically disposed bore 46 as formed therein. The upper end of this pivotally mounted catch 45 has pivotally connected therewith, the lower end of a lever 47, this lever in turn being also pivotally mounted within the bore 46 and has formed upon its upper extremity an angularly disposed portion which carries upon the outer extremity thereof a circular target 48. The upper portion of the lever 47 is normally held outwardly by means of an expansible coiled spring 49 which is seated within a suitable recess formed in the body of the 105 110 115 120 125 130

rider and bears against the adjacent portion of said lever. A coiled spring 50 is mounted within communicating pockets 51 and 52, which are formed within the bodies 5 of the horse and rider and provide means whereby dislodgment of the rider will be effected when the catch 45 is disengaged from its keeper 44. Upon striking the target 48, the lever 47 is accordingly 10 rocked and the release of the pivotal catch 45 from the keeper 44 effected. The manikin 38 thus rocks upon the hinge 43 and the falling of the manikin from the horse is simulated. The manikin is automatically re- 15 mounted by the engagement of a roller 53 which is journaled in bracket 54 on the shoulder of the manikin, with an inclined trackway 55. The trackway 55 is mounted upon a plurality of uprights 56 which are 20 supported on the top 1. It is to be also noted that in practice the inclined track 55 will be so arranged upon its supporting uprights 56, that the sprocket chain 9 is gradually approached, as the trackway reaches its high- 25 est point. By this means, it will be apparent that when the manikin is dislodged from the horse, the roller 53 will engage the elevated inclined track 55 and as the horse is advanced, the roller 53 will be carried up- 30 wardly over said trackway, thus causing the manikin to be gradually returned to an upright position, whereupon, the pivotal catch 45 will again engage its keeper 44 and the particular target will be again ready for dis- 35 play before the opening 4. By so arranging the trackway 55 that the same gradually approaches the chain 9 as shown in Fig. 1, it will be evident that the decreased distance between the rollers 53 and the body of the 40 horse caused by the gradual upward movement of the rider, will be compensated for.

In reviewing the operation of the construction, the chains 9 and 10 will be alternately driven by means of their respective 45 gears 19 and 20, causing the pivotally mounted legs of the various horses 34 to be successively advanced and making the animals appear as though they were walking. Continuous movement of the chains 9 and 50 10, will cause the various horses and riders to be successively displayed before the opening 4 as arranged within the screen or division wall 3. When in this position, they are fired at and should the target 48 be struck 55 by one of the projectiles, the target will be forced rearwardly causing the lever 47 to release the pivotal catch 45 from its keeper 44 and cause the manikin 38 to be rocked on the hinge 43. Continued movement of the 60 chains 9 and 10 will bring a second horse and rider before the opening 4, which in turn may be fired at. As the dislodged body of the rider upon the preceding horse is moved forwardly, it will be evident, that 65 the roller 53 will travel upon the inclined

track 55 and that the body of the rider will be gradually moved into upright position and that the pivotal catch 45 will be again engaged with its respective keeper 44, whereupon this particular target is again ready 70 for display before the opening 4.

To provide for means whereby those targets as not adjacent the opening 4 of the division wall 3 may be protected from the firing, a partition 57 is arranged between 75 the forward and rear portions of the platform and provides the necessary shelter.

It will of course, be understood that any number of horses and riders may be arranged upon the platform to be driven by 80 the chains 9 and 10; also that the propelling means may be driven at the desired speed whereby the pivoted mounted legs of the various horses will be actuated accordingly, thus allowing the operator to control the movement thereof and give the same the appearance of either walking or trotting.

If so desired, the sprocket chains 9 and 10 may be dispensed with and the sprocket wheels 17 and 18 eliminated in order that 90 the conventional form of frictional belt and gearing may be substituted therefor. This is of course optional with the user.

Other modes of applying the principle of my invention, may be employed instead of the one explained, changes being made as regards the mechanism herein disclosed, provided the means stated by any of the following claims or the equivalent of said 95 stated means be employed.

I therefore particularly point out and distinctly claim as my invention:—

1. A target including a base, an object movable over the base, supporting members for the object, carriers for the supporting members, and means for imparting a step-by-step movement to the carriers.

2. A target including a base, an object movable over the base, supporting members for the object, carriers for the supporting members, and means for alternately advancing the carriers.

3. A target including a base, an object movable over the base, supporting members for the object, carriers for the supporting members, and means for intermittently and alternately moving the carriers to impart a step-by-step movement to the supporting members.

4. A target, including a base, an object movable over the base, and automatically operated means for intermittently advancing the object.

5. A target, including a base, an object movable over the base, a flexible and movable carrier for supporting the object, means for guiding the carrier in a prescribed path, and means for automatically actuating the carrier intermittently.

6. A target including a base, an object

movable over the base, the object having pairs of pivoted legs, a flexible and movable mounting for supporting each of the pairs of legs, means for guiding the flexible mountings in prescribed paths, and means for actuating the respective flexible mountings alternately and intermittently.

7. A target including a base, an object movable over the base, the object having 10 pivoted pairs of legs, flexible mountings for each of the pairs of legs, connecting links between the legs and the flexible mounting, guides for directing the flexible mountings in a prescribed path, sprocket devices in engagement with each of the flexible mountings, mutilated gears for actuating the sprocket devices alternately and intermittently, and means for driving the mutilated gears.

15 8. A target, comprising a plurality of movable objects carried upon a base, figures pivotally secured to said objects, catches carried by said figures, keepers affixed to said objects for receiving said catches, bull's eyes arranged upon said catches adapted to disengage the same from said keepers when struck by a projectile to permit the figures to be dislodged from said objects, and resilient means arranged between said objects and 25 said figures for facilitating the dislodgment of the latter.

9. A target comprising a plurality of movable objects having pivotally mounted leg portions, means for successively advancing said leg portions and causing said objects to be moved, figures pivotally secured to the objects adapted to be dislodged therefrom when struck by a projectile, and means for automatically moving said figures to 35 normal position upon said objects subsequent to dislodgment therefrom.

10. A target comprising a plurality of movable objects carried upon a base, pivotally mounted leg portions carried by said 45 objects, means arranged upon said base for alternately moving said leg portions whereby said objects will be advanced, figures pivotally secured to said objects adapted to be dislodged therefrom when struck by a projectile, and means for automatically moving said figures to normal positions upon 50 said objects subsequent to dislodgment therefrom.

11. A target comprising a base, a plurality of movable objects carried upon said base having pivotally mounted leg portions, means arranged upon said base and engaged with the pivotally mounted leg portions for

alternately operating the same whereby said objects will be advanced, figures pivotally secured to said objects, means arranged upon said figures for normally maintaining the same in upright position upon said objects, bull's eyes affixed to said means adapted to disengage the same when struck by a projectile to permit said figure to be dislodged from said object, and means for automatically moving said figures to normal position upon said objects subsequent to dislodgment therefrom.

70 12. A target, comprising a base, a plurality of movable objects arranged upon said base having pivotally mounted leg portions, means carried by the base and connected with said pivotal leg portions whereby the same will be alternately operated for advancing said objects, figures pivotally secured to said objects, catches carried by said figures, keepers affixed to said objects for receiving said catches, bull's eyes arranged upon said catches adapted to release the same from the keepers when struck by a projectile, resilient means interposed between the objects and the figures for facilitating the dislodgment thereof when said catches are released, and means arranged adjacent said objects for automatically moving the same to normal position thereupon subsequent to dislodgment therefrom.

75 13. A target comprising a base, a plurality of movable objects arranged upon said base having pivotally mounted leg portions, means carried by said base and connected with said pivotally mounted leg portions whereby the same will be alternately operated for advancing said objects, figures pivotally secured to said objects, catches carried by said figures, keepers affixed to said objects for receiving said catches, bull's eyes arranged upon said catches adapted to 80 release the same when struck by a projectile, spring means interposed between said objects and said figures for facilitating the dislodgment of the figures from the objects when said catches are released, and an inclined trackway arranged adjacent said objects for receiving and supporting a portion of said figures and automatically moving the same to normal position upon said objects subsequent to dislodgment therefrom.

85 110 In testimony whereof I affix my signature in presence of two witnesses.
